UNITED STATES PATENT OFFICE.

JOEL ELLIS PRIESTER, OF HARRISBURG, TEXAS.

BOILER ATTACHMENT.

1,114,182.

Specification of Letters Patent.

Patented Oct. 20, 1914.

Application filed June 28, 1913. Serial No. 776,318.

To all whom it may concern:

Be it known that I, JOEL ELLIS PRIESTER, a citizen of the United States, residing at Harrisburg, in the county of Harris and 5 State of Texas, have invented new and useful Improvements in Boiler Attachments, of which the following is a specification.

This invention relates to new and useful improvements in boiler attachments.

10 The object of the invention is to produce a thermostatic device of simple and improved construction which may be utilized for the purpose of actuating a valve governing the steam supply to the pump or injector.

A further object of the invention is to provide simple and improved means for cooling the thermostatic device so that the operation of the parts actuated by the thermostat 20 will not be extended beyond the reasonable time limit.

With these and other ends in view which will readily appear as the nature of the invention is better understood, the same consists in the improved construction and novel 25 arrangement and combination of parts which will be hereinafter fully described and particularly pointed out in the claims.

In the accompanying drawings has been 30 illustrated a simple and preferred form of the invention, it being, however, understood that no limitation is necessarily made to the precise structural details therein exhibited, but that changes, alterations and modifications 35 within the scope of the claims may be resorted to when desired.

In the drawings, Figure 1 is a front elevation of the device and Fig. 2 is a sectional view taken on the line 8—8 of Fig. 1.

40 Corresponding parts in the several figures are denoted by like characters of reference.

As illustrated in the figures the upright expansion tube, here designated by 50, and which is connected with the boiler A supports 45 at its upper end a lever K' and near its lower end a bracket K'' having oppositely extending arms. The short arm of said lever and bracket are connected together by a link 51. The long arm of the bracket K'' supports a lever L'', one arm of which, 52, which extends outwardly with respect to the pipe 50 is connected with the long arm of the lever K' by a link 53. The link 53 is connected with the arm 52 at a point 55 mediate the fulcrum of the lever and the extremity of the arm, and said extremity is

connected by a link 54 with the handle 55 of a valve 56 in a pipe 57 which connects the steam space of the boiler with the pump or injector.

Supported adjacent to the expansion pipe 50 is a water pipe 58 terminating at its upper end in a goose neck 59 adapted to discharge a current or spray of water directly upon said expansion pipe. The pipe 58 communicates with the discharge of the pump, and said pipe is provided with a valve 60, the stem of which has an operating crank or handle 61 disposed in the path of the short arm 62 of the lever L'', said arm being provided with an upwardly extending trip member 63 which directly engages the crank 61.

The parts are constructed, arranged and assembled in such a manner that when the pipe 50 expands longitudinally, owing to the lowering of the water within the boiler and the substitution of steam for water within said pipe consequent thereon, the long arm of the lever K' will exert a pulling action on the long arm of the lever L'', thereby actuating, through the link 54, the valve 56 and serving to admit steam through the pipe 57 to the pump or injector which is thus set in motion. At the same time the trip member 63 will engage the handle 61 of the valve 60 which is thus opened for the passage of water through the pipe 58, the water being discharged over on the upper end of the expansion pipe 50 and serving to cool the latter, and thereby interrupting the operation of the pump by causing the restoration of the parts to initial position without being protracted beyond the desired time limit.

It will be noted that the trip member 63 of the arm 62 is normally situated at some little distance from the valve crank 61, so that the latter will not be operated for the admission of water through the pipe 58 until the valve 56 has been opened for some little time, the operation being, of course, effected gradually; a suitable spring 64 may be utilized to restore the valve 60 to the closed or obstructing position when the member 61 is relieved from the pressure of the trip member 63.

Having thus described the invention, what is claimed as new, is:—

1. In a device of the character described, 110 an upright expansion tube connected at its lower end with a boiler at a predetermined

low-water level and having a closed upper end, a suitably supported lever adapted to be actuated by the expansion and contraction of the tube, a water supply pipe supported in proximity to the expansion tube and adapted to discharge thereon, and a valve on said water supply pipe adapted to be operated by the lever.

2. In a device of the character described, an upright expansion tube connected at its lower end with a boiler at a predetermined low-water level and having a closed upper end, a suitably supported lever adapted to be actuated by the expansion and contraction of the tube; a water supply pipe disposed in proximity to the expansion tube and adapted to discharge thereon, means operable by live steam for injecting water into the boiler, a pipe connecting said means with the steam space of the boiler, a valve on said steam pipe, a valve on the water pipe; and means connecting the arms of the

lever with said valves to open and close the latter when the lever is actuated by the expansion and contraction of the expansion tube. 25

3. In a device of the class described, a boiler, an upright tubular member connected with said boiler at a predetermined low-water level and constituting an expansion tube, said tubular member being closed at its upper end, a water supply tube supported in proximity to the expansion tube and discharging thereon, a self-closing valve on the water supply tube, and means operable by the expansion of the expansion tube for opening the self-closing valve. 30 35

In testimony whereof I affix my signature in presence of two witnesses.

JOËL ELLIS PRIESTER.
